(57) **CLAIM**

The ornamental design for a smoking apparatus with removable funnel, as shown and described.

DESCRIPTION

FIG. 1 is a perspective view of a smoking apparatus with removable funnel.

FIG. 2 is a front view of the smoking apparatus with removable funnel.

FIG. 3 is a back view of the smoking apparatus with removable funnel.

FIG. 4 is a right side view of the smoking apparatus with removable funnel.

FIG. 5 is a left side view of the smoking apparatus with removable funnel.

FIG. 6 is a top view of the smoking apparatus with removable funnel.

FIG. 7 is a bottom view of the smoking apparatus with removable funnel; and,

FIG. 8 is an exploded perspective view of the smoking apparatus with removable funnel.

The broken lines in the drawings depict portions of the smoking apparatus with removable funnel that form no part of the claimed design.
